UNITED STATES PATENT OFFICE.

ERNST GOTTHARD ERICSSON LANGBERT, OF STOCKHOLM, SWEDEN.

REFRIGERATING APPARATUS.

1,375,396.

Specification of Letters Patent. Patented Apr. 19, 1921.

Application filed December 26, 1918. Serial No. 268,382.

To all whom it may concern:

Be it known that I, ERNST GOTTHARD ERICSSON LANGBERT, engineer, subject of the King of Sweden, residing at Stockholm,

5 Sweden, have invented certain new and useful Improvements in Refrigerating Apparatus, of which the following is a specification.

The invention relates to a refrigerating apparatus of the kind, in which the cooling is effected by means of a liquid cooling agent, which is vaporized by reduction of pressure, while absorbing heat from the body to be cooled, and at the same time storing cold in a cold accumulator.

Apparatus of this kind are worked in such a way, that during the working periods, periods of cold generation, either the whole or a part of the cold generated by means of a compressor is being accumulated in the cold accumulator, while another part is used for direct cooling, whereas the cooling during idle hours is effected exclusively by means of the cold accumulator. The non-refrigerating apparatus of this kind have the disadvantage, that they may be only worked economically by means of a compressor until the liquid of the cold accumulator has been transformed into a solid condition, since the frozen liquid forms a bad conductor for transmitting heat. In some cases, however, it is desirable to effect cooling during long periods of time substantially by generating heat by means of a compressor, whereas the cold accumulator only serves to keep the temperature down during short interruptions of the service. Apparatus would not be very economical, if they were carried out according to the known apparatus. The

40 present invention, however, provides for an economical operation of refrigerating plants of this kind. The invention principally consists in the cold accumulator being arranged inside of the cooling elements in such a way that a space is formed between the cold accumulator and the outer wall of the cooling element, which space serves to receive the liquid cooling agent so that the cooling agent may act as a heat conductor during the idle hours, when the cooling is effected by means of the cold accumulator. By this construction of the cold accumulator an efficient transmission of heat is secured under all circumstances, as the transmission of heat may take place freely during the working periods between the cooling agent and

the body to be cooled directly through the wall of the cooling element and during the idle hours between the cold accumulator and the body to be cooled through the medium 60 of the cooling agent, the latter then serving only as a heat conductor.

The invention is particularly intended for railway refrigerating apparatus, in which the compressor is driven from the wheel 65 axle of the car, although as apparent the apparatus may be used with advantage in stationary refrigerating plants.

The cooling agent may consist of methyl alcohol or ethyl chlorid.

70 The accompanying drawing shows a section of a cooling element according to this invention.

The cooling element consists of a cylindrical receptacle or casing 1 closed at its 75 lower end and, at its opposite end, connected to and communicating with a vacuum piping 2 common to a plurality of cooling elements, through a pipe connection 3. At the outer side of the casing longitudinal ribs 4 80 are provided in order to obtain a large cooling surface against the surrounding air. Inside the casing 1 a cylindrical receptacle 5 is provided centrally with respect to the casing, said receptacle being secured to a 85 supporting cross 6 in the pipe connection 3 by means of a nut 7 in such a way that a free space is left at 8 between the receptacle 5 and the pipe connection 3. The cooling agent is supplied to the space 9 between the 90 receptacle 4 and the casing 1 through a pipe 10 which may be controlled in known manner by means of a check-valve. The cooling agent stands normally at about the level 11. The receptacle 5 is filled with 95 water or brine.

During the working periods of the plant cold is produced in known manner by the vaporization of the cooling agent caused by the vacuum in the pipe 2. Heat is then first 100 absorbed partly from the content of the cold accumulator 5 and partly from the surrounding air in chamber to be cooled. After the temperature of the content of the accumulator has been lowered to the temperature 105 of the cooling agent heat is absorbed only from the surrounding air. Thus, during the working periods the air is cooled exclusively by a direct transmission of heat from the air to the cooling agent. During the idle hours 110 on the other hand the transmission of heat takes place through the medium of the cool-

ing agent in the space 9 the cooling agent then only serving as a conductor of heat.

Claims.

1. A cooling apparatus having an outer 5 cooling surface and consisting of an outer heat conducting casing adapted to contain a refrigerant, a receptacle adapted to contain a congealable substance and arranged inside said casing so as to be surrounded 10 by the refrigerant, and means for circulating the refrigerant through the casing.

2. A cooling apparatus having an outer 15 cooling surface consisting of an outer heat conducting cylindrical casing having ribs at its outer surface and constructed to contain a refrigerant, a cylindrical receptacle adapted to contain a congealable substance and arranged centrally within and spaced from the walls of said casing, a vacuum piping, 20 means for connecting the casing at its upper end with said vacuum piping, and means for circulating a refrigerant through the space between the casing and the receptacle.

3. In an apparatus of the character de- 25 scribed, a casing provided with longitudinal

and radially arranged ribs, a receptacle suspended within and spaced from the walls and bottom of the casing adapted to contain a congealable substance, and means for circulating a refrigerant through the space be- 30 tween the casing and receptacle.

4. In an apparatus of the character de- 35 scribed, the combination with a vacuum piping, a connection interposed therein, and a support in the connection, of a cylindri- 40 cal casing having its open upper end connected to the connection, a cylindrical receptacle suspended from the support and arranged within and spaced from the walls and bottom of the casing adapted to contain a congealable substance, and means for circulating a refrigerant through the space be- 45 tween the casing and receptacle.

In testimony whereof I affix my signature in presence of two witnesses.

ERNST GOTTHARD ERICSSON LANGBERT.
